UNITED STATES PATENT OFFICE.

WARREN B. FLANDERS, OF PHILADELPHIA, PENNSYLVANIA, ASSIGNOR TO WESTINGHOUSE ELECTRIC AND MANUFACTURING COMPANY, A CORPORATION OF PENNSYLVANIA.

GLAND-CONTROL MECHANISM.

Application filed April 2, 1923. Serial No. 629,526.

My invention relates to glands for insuring a seal between a rotor and its casing such, for example, as used in connection with steam turbines and like apparatus, and 5 it has for its object to provide apparatus of this character which shall utilize fluids of different gravities and which shall incorporate means responsive to the speed of the apparatus or machine for changing from one 10 fluid to another dependent upon the speed of the apparatus.

A further object of my invention is to provide apparatus of the character referred to which shall assure the complete opening 15 and closing of the valves controlling the supplies of fluids to the gland upon a predetermined change in speed.

Apparatus made in accordance with my invention is illustrated in the accompanying 20 drawings, forming a part of this application, in which Fig. 1 is a view showing my improved gland control mechanism associated with a gland and with a pressure-developing device; Fig. 2 is a sectional view taken along 25 the line II—II of Fig. 1; Fig. 3 is a sectional view taken along the line III—III of Fig. 1; and Fig. 4 is a diagrammatic sectional view of a modified form of my invention.

Water is ordinarily used in the glands of a steam turbine to seal the interior thereof from the outside; however, when the speed of a turbine diminishes to a given extent the 30 centrifugal force imparted to the water is insufficient to cause the latter to constitute an effective seal. Therefore, glands of this type ordinarily incorporate a water gland portion for operation at normal speeds and a steam gland portion which is effective 35 when the turbine speed drops below a value at which the water seal may be maintained.

My invention relates to automatic means which is responsive to the speed of the turbine or like apparatus to automatically shift 40 valves which control the water and steam supplied to the gland portions. A particular feature of this automatic means is a valve mechanism which is moved initially by pressure-responsive means to either assure 45 building-up or the relief of pressure in a pressure-operated mechanism for opening and closing the supply valves, the initial movement of the pressure-operated mechanism resulting in such a movement of the

controlling valve that a full traverse of the 55 mechanism and of the supply valves in opening and closing directions is assured.

Referring now to the drawings for a better understanding of my invention, in Fig. 1, I show my improved gland-control 60 mechanism, at 10, for controlling the supply of fluids of different gravities, for example, steam and water, to the gland, at 11, arranged between a rotor 12 and a casing 13, for example, of a steam turbine. The 65 gland-control mechanism, at 10, incorporates a suitable pressure-responsive element which receives fluid under pressure from the impeller 14 of the impeller pump, at 15, the impeller being carried by a shaft 16 which is 70 operated by the machine so that the pressure of fluid developed varies as a function of the speed of the machine.

The gland-control mechanism includes a pressure-responsive element which, as may 75 be seen from Fig. 2, consists of a movable abutment or piston 17, within the cylinder 18, the space beneath the piston or abutment 20 communicating with the supply line 19 connected to the impeller pump 15. A spring 80 20 is arranged above the piston or abutment 17 for resisting movement thereof in response to increases in fluid pressure and to assure movement thereof under its influence when the fluid pressure diminishes. The piston or 85 abutment 17 is preferably provided with a projection 21 which limits movement thereof under the influence of the spring 20. The piston or abutment 17 carries a stem 22 which passes through the head 23 of the 90 cylinder 18 and such stem is connected to a floating lever 25, which is pivotally connected to the pilot valve mechanism, at 26, and to the pressure operated mechanism, at 27.

The pilot valve mechanism, at 26, includes an inner pilot valve 28 having piston portions 29, 30 and 31, arranged within the valve cylinder 32 and serving to control the supply of fluid under pressure passing from 100 the port or passage 33, communicating with the pressure supply line 19, to the pressure supply passage 34, which leads to the operated mechanism, at 27, and the exhaust of fluid from the operated mechanism through 105 the passages 34 and 35.

The pressure-operated mechanism, at 27, includes a cylinder 36 containing a movable

abutment or piston 37 which is adapted to be acted upon by fluid under pressure received from the line 19 when the piston portion 30 moves upwardly to interrupt communication between the passages 34 and 35 and to establish communication between the passages 33 and 34. Downward movement of the operating piston or abutment 37 is secured by means of a spring 38, this spring being effective to secure downward movement of the piston or abutment 37 when the passageway 34 is placed in communication with the exhaust passage 35.

The operating piston or abutment 37 is provided with a stem 39 which extends through the cover 40 of the cylinder 36, and it is provided with a member 41 to which the floating lever 25 aforesaid is pivotally connected.

20 From the structure described, it will be apparent that when the pilot valve 28 is moved to establish communication between the pressure supply passage 33 and the passage 34 and to interrupt communication of
25 the latter passage with the exhaust passage 35, the operating piston or abutment 37 is moved upwardly and that movement of the latter element in that direction results in further movement of the piston
30 valve 28 in order to maintain communication between the passages 33 and 34 to assure a quick and complete traverse movement of the operating piston or abutment 37.

35 On the other hand, with a decline in pressure of fluid, the pressure-responsive piston or abutment 17 moves downwardly so as to place the passage 34 of the operating cylinder 36 in communication with the exhaust passage 35, thereby permitting of the operating piston or abutment 37 moving downwardly under the influence of the spring 37. This downward movement of the operating piston or abutment 37 results in downward movement of the left-hand end of the floating lever 25, with the result that the pilot valve 28 is moved downwardly to assure the maintenance of communication between the passage 34 and the exhaust passage 35 to secure a full traverse movement of the operating piston or abutment 37 under the influence of the spring 38. A stud 43 is carried by the operating piston or abutment 37 to limit movement of the latter due to the spring 38.

The operating piston 37 contains a stem element 44 arranged within the stem 39 and having a head 45 at its lower end, and a spring 46 is arranged between the head 45 and a cap 47 carried by the operating piston or abutment 37. The upper end of the stem 44 is pivotally connected to a lever 48, fulcrumed, at 49, and pivotally connected to the stems 51 and 52 of the steam and water supply valves 53 and 54, respectively. The

spring 46 serves to maintain the valves 53 and 54 seated as well as to assist in taking up looseness in the leverage connections.

The steam valve comprises a suitable housing 55 having an inlet chamber 56, which communicates with the steam supply line 57. This housing is provided with an intermediate partition 58 having a valve seat 59 for the valve 53; and, above the partition 58, the housing is provided with an outlet chamber 60, which communicates with the line 61 for supplying steam to the steam gland portion 62 of the gland, at 11. A spring 63 is preferably arranged within the chamber 60 and around the stem 51 to exert its force against the valve 53 so that the latter may firmly seat against the seat 59. From the structure, it will be apparent that the valve 53 is opened upon upward movement and closed upon downward movement.

Turning now to the water valve construction, the housing 65 is provided with water supply chamber 66, communicating with the water supply line 67 and with a gland supply chamber 68, the latter communicating with the water gland portion 69 of the gland, at 11, by way of the water line 70, the chambers 66 and 68 being separated by a partition 71, which has a seat 72 for the valve 54, connected to the stem 52. A spring 73 is arranged beneath the valve 54 and it tends to move the latter upwardly to fully seat it.

From the apparatus described in Figs. 1, 2 and 3, the operation thereof will be apparent. The pressure-responsive element or piston 17 moves in response to pressure supplied by the pump 15 and by the spring 20 to move the pilot or piston valve 28 to establish communication of the passage 34 either with the pressure supply passage 33 or with the exhaust passage 35 and to interrupt communication between the passage 34 and the other of said passages 33 and 35. Upon movement of the pilot valve 28 in this way, the operating piston or abutment 37 is either moved up, under the influence of fluid under pressure, or it is moved down by the spring 38, when the space beneath the operating piston is placed in communication with the exhaust. The connection of the pressure-responsive element 17, the pilot valve 28, and the operating piston or abutment 37 to a floating lever 25 assures that, upon initial movement of the pilot valve to supply fluid under pressure to the operating cylinder or to exhaust fluid therefrom, the operating piston or abutment 37 moves the piston valve 28 in such a direction as to maintain the initial fluid connection so that the operating piston or abutment may be quickly traversed in either direction to its fullest extent. A slight movement of the pilot valve is, therefore, sufficient to effect the desired communication.

cient to secure the desired initial operation of the operating piston, and after such operation has started the pilot valve is so moved as to assure the continued operation of the operated piston until the latter has effected a complete stroke.

Upward movement of the operating piston 37 results in movement of the lever 48 about its fulcrum 49 to move the valve rods 51 and 52 downwardly so as to close the steam valve and to open the water valve. In other words, when the turbine speed acquires a sufficient value to develop fluid under pressure which is sufficient to move the pressure-responsive element or piston 17 in an upward direction to a sufficient extent, the operating piston 37 moves upwardly to close the steam valve and to fully open the water valve. It will be noted that, during the closure of the steam valve and the opening of the water valve, both valves are open for a period. This is as it should be for the reason that the supply of both fluids to the gland at 11 should never be interrupted. Upon downward movement of the operating piston 37 in response to a decrease in fluid pressure incident to reduced turbine speed, the valve stems 51 and 52 are moved upwardly to open the steam valve and to close the water valve.

It will be noted that a spring 46 is incorporated in the connection between the operating piston 37 and the stem 44 so that upward movement of the operating piston may be communicated to the lever 48 and to the valve stems 51 and 52 in a yielding manner. This assures that, upon upward movement of the operating piston 37 to its fullest extent, the valve 53 shall be maintained in contact with its seat 59 under the tension of said spring. This effect is also assisted by the spring 63 surrounding the valve stem 51. Also the use of the spring 46 serves as an adjustable connection so that the stroke of the operating piston 37 may possibly be longer than that required to operate the valves. In other words, downward movement of the operating piston 37 may be limited by properly adjusting the stud 43, whereas upward movement of the stem 44 would be limited by the amount required to secure closure of the steam valve and opening of the water valve. In this way, the range of movement of the stem 44 may be less than that of the operating piston 37, the difference being absorbed by lengthening and shortening of the spring 46. Also the spring 46 may serve to absorb looseness in the connections between the stem 44 and the valve stems 51 and 52.

The spring 63, arranged around the stem 51 of the steam valve 53, assists in urging the latter toward its seat 59, the valve 53 preferably incorporating a connection 53' with the stem 51 so that the valve may be fully

seated without sticking or jamming, the spring 63 assuring of a tight seating thereof.

The water valve 54 also preferably includes a connection 54' with the stem 52 so that the valve 54 may be fully seated without binding or sticking, and the spring 73 serves to secure seating of this valve when the stems 51 and 52 move upwardly incident to downward movement of the operating piston 37.

Referring to the modified form of my invention shown in Fig. 4, I show a gland, at 11, and a centrifugal impeller pump, at 15, similar to those shown in Fig. 1, cooperating with a slightly different type of apparatus for securing a sudden change in the supply of water and steam for the gland dependent upon the turbine speed. In this view, I show the centrifugal pump connection 19 leading to a pressure-responsive device, at 75, including a cylinder 76 and an operating piston 77. Fluid under pressure acts beneath the piston 77 to move the latter upwardly and a spring 78 cooperates with the upper side of the piston to move it downwardly.

The operating piston 77 is provided with a stem 79, which is provided with an interior shoulder 80 fitting above the head 81 of a stem 82, a spring 83 being arranged between the stem 79 and an adjustable abutment 84 carried by the stem 82. This construction permits of a yieldable transmission of movement from the stem 79 to the stem 82 upon upward movement of the former and of a positive pull of the stem 82 by the stem 79 when the shoulder 80 is in contact with the head 81.

The stem 82 is pivotally connected, at 85, to a lever 86, fulcrummed at 87, and pivotally connected, at 88, to a stem 89, which has collars 90 between which fits one end of the lever 91, fulcrummed at 92, and having its end 93 engaging between abutments 94 of the valve member 95, which controls the exhaust of fluid from beneath the operating piston 96.

The operating piston 96 is arranged within an operating cylinder 97 having a steam supply port 98 thereabove, said port communicating with a steam supply line 98'. The operating piston 96 is provided with a portion 99 of smaller diameter projecting upwardly and terminating in a valve portion 100, cooperating with a seat 101 carried by the housing, which provides a space 102 above the seat 101 and communicating with the passageway 103 leading to the steam line 61.

The operating piston 96 is carried by a hollow stem 104, which incorporates a seat 105 and a passageway 106 communicating with the space beneath the operating piston 96.

As the piston area beneath the piston 96

is greater than that above the piston, with movement of the valve 95 to fit against the seat 105, steam which leaks by the piston builds up pressure therebelow resulting in upward movement of the piston to move the valve 100 into contact with its seat 101 to interrupt the supply of steam from the passage 98 to the passages or chambers 102 and 103. On the other hand, if the valve 95 is moved upwardly from its seat 105, pressure beneath the piston 97 is suddenly relieved through the passage 106, with the result that the piston moves downwardly under the influence of pressure above it so as to establish communication between the steam supply and the steam gland portion 62. Steam which passes through the passage 106 and by the seat 105 enters the chamber 106' from which it escapes by the outlet 106".

The stem 104 is connected to a water valve 106', which controls communication between the water inlet 107 and the water outlet 108 communicating with the water line 70 leading to the water gland portion 69. A lost-motion connection 110 is preferably provided between the stem 104 and the water valve 106 so that the effective movement of the stem 104 may be greater than that of the valve, thereby assuring that the water valve 106' will be closed by its spring 111 when the stem 104 is moved downwardly sufficiently so that the shoulder 112 ceases to contact with the lower face of the head 113.

In principle, the operation of apparatus illustrated in Fig. 4 is similar to that heretofore described. As soon as the turbine speed declines so as to maintain pressure below a predetermined amount, the pressure-responsive piston 77 moves downwardly to pull the lever 86 downwardly and to move the valve 95 upwardly from its seat 105. Thereupon, pressure beneath the operating piston 96 is immediately relieved, resulting in sudden downward movement of the piston to establish communication between the steam supply 98' and the steam gland 61. It will be noted that just as soon as the valve 95 is unseated from its seat 105 in the slightest degree, movement of the operating piston 96 takes place in such a direction as to assist in the relief of pressure below the piston, thereby assuring full traverse movement of the latter so that the steam valve may be opened and the water valve 106 may be closed under the influence of the spring 111. Assuming that the turbine speed should increase so as to develop pressure of fluid by the pump 15 beyond a predetermined amount, then the pressure-responsive piston 77 moves upwardly and the upward motion thereof is transmitted through the spring 83 to the stem 82, resulting in upward movement of the right-hand end of the lever 86, upward movement of the stem 89, and downward movement of the valve 95.

Just as soon as the valve 95 comes in contact with its seat 105, exhaust from beneath the piston 96 is cut off and pressure beneath the piston starts to build up. When the pressure beneath the piston 96 becomes sufficiently great, the piston moves upwardly in a differential manner; and, it will be noted that the movement is in such a direction as to secure cooperation of the seat 105 with the valve 95, thereby assuring closure of the exhaust for the full upward traverse movement.

From the apparatus described in connection with Fig. 4, it will be apparent that the pressure-responsive device is really called upon to give only a very slight or incipient movement to the valve 95 and that the resultant downward or upward movement of the stem 104 in consequence of relief of pressure beneath the piston 96 or the building up of pressure therebeneath takes place in such a direction as to secure assistance in that the stem 104 moves in such a direction as to secure wider opening of the valve 95 in case of exhaust or a tendency to maintain closure of the valve in case of building up of pressure beneath the piston 96. In a similar way, the pilot valve of Figs. 1 to 3, inclusive, is merely given an incipient movement by the pressure-responsive device to give the proper fluid connection to the operating cylinder, the resulting movement of the operating piston moving the valve to ensure a complete traverse of the piston.

From the apparatus described, it will be apparent that I have provided apparatus wherein only a slight movement of a pressure-responsive device is sufficient to secure complete traverse movement to open or to close steam and water valves for steam and water gland portions of a gland of a steam turbine or like apparatus.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. The combination with a machine requiring fluids of different gravities in accordance with the speed thereof, of lines for supplying the fluids of different gravities, valves in the lines, speed-responsive means operated by the machine, an operating device for opening and closing the valves, a control means operated by the speed-responsive device to control the movement of the operating device, and means connected with the operating device for accelerating and assuring complete movement of the control means.

2. The combination with a machine requiring fluids of different gravities in accordance with the speed thereof, of lines for supplying the fluids of different gravities, 5 valves in the lines, speed-responsive means operated by the machine, an operating device including an abutment connected to the valves for opening and closing the latter, pressure means for operating the abutment in one direction when the pressure at the other side of the abutment declines, and a control valve operated by the speed-responsive device to control the building up or relief of pressure at said other side of 10 the abutment and including an element movable by the abutment to assure rapid building up or relief of pressure and the complete traverse of the abutment to open and to close the valves.
3. The combination with a machine requiring fluids of different gravities in accordance with the speed thereof, lines for supplying the fluids of different gravities, valves in the lines, an operating piston for 15 opening and closing the valves, pressure means effective to move the operating piston in one direction, and a valve for controlling the building up and relief of pressure effective on the piston in the other direction and including an element movable by the piston to assure the rapid building up and relief of pressure and the complete traverse of the piston to open and close the valves.
4. The combination with a gland construction for a machine and having steam and water gland portions, lines for supplying water and steam to the glands, valves in the lines, a movable abutment for opening and closing the valves, pressure means effective to move the abutment in one direction, a valve for controlling the building up of fluid pressure to overcome said pressure means to secure movement of the abutment in the other direction and for relieving the fluid pressure to render said pressure means effective, said valve including an element which is moved by the abutment to assure sufficient relief or application of pressure to the abutment to secure full traverse movement of the latter and full opening and closing movement of said valves, a pressure-responsive device cooperating with said controlling valve, and means operated by the machine for developing pressure of fluid which varies as a function of the speed of the machine for application to said pressure-responsive device.
5. The combination with a gland construction for a machine and having steam and water gland portions, lines for supplying steam and water to the gland portions, valves in the lines, a movable element for opening and closing the valves, pressure means cooperating with one side of the ele- 60 65 70 75 80 85 90 95 100 105 110 115 120 125 130
- ment, means for building up and for relieving pressure on the other side of the element, pressure-responsive means for controlling the operation of the latter means, and means operated by the machine for developing pressure of fluid which varies as a function of the speed thereof and for supplying such fluid to the pressure-responsive means.
6. The combination with a gland construction for a machine and having steam and water gland portions, of lines for supplying steam and water to the gland portions, valves in the lines, an operating piston for opening and closing the valves, a pressure-responsive device, means for developing pressure of fluid in accordance with the speed of the machine for application to the pressure-responsive device, a controlling valve initially moved in opening and closing directions by said pressure-responsive device, and a connection between the operating piston and the controlling valve to assist in opening and closing operations to assure the complete and quick traverse of the operating piston in either direction.
7. The combination with a gland construction for a machine and having gland portions for fluids of different gravities, of fluid supply lines for the gland portions, valves in the supply lines, means for developing pressure of fluid which varies as a function of the speed of the machine, fluid-pressure operated mechanism for opening and closing the valves, a valve for controlling the admission of fluid under pressure to said operating mechanism and the exhaust of fluid therefrom, means responsive to the pressure of fluid developed by said pressure-developing means to secure movement of the controlling valve to an initial position to supply or exhaust fluid from the operated mechanism, and a connection between the operated mechanism and the controlling valve to secure movement of the latter in such a direction as to assure the continuance of the supply of pressure fluid to the operated mechanism or the exhaust of fluid therefrom throughout the traverse movement thereof.
8. A fluid-pressure operated mechanism comprising an operated element, a valve for controlling the admission and exhaust of pressure fluid to the operated element, a pressure-responsive device, a connection between the pressure-responsive device and the valve whereby the latter may be moved to an initial pressure supply or exhausting position for the operated element, and a connection between the operated element and the valve to assure movement of the valve in such a direction as to assure a continuance of the supply or exhaust connection with the operated element throughout the traverse movement thereof.

9. Pressure-operated mechanism comprising an operating cylinder, an operating piston within the cylinder, a spring at one side of the piston, a fluid-supply passage communicating with the operating cylinder at the other side of the piston, fluid pressure supply and exhaust passages, a valve for controlling communication of the cylinder supply passage with the exhaust and pressure supply passages, a pressure-responsive device for moving the valve to establish initial communication between the operating cylinder with the exhaust passage or with the pressure-supply passage, and a connection between the operating piston and the valve to assure movement of the latter in such a direction as to secure continuance of communication of the operating cylinder either with the pressure-supply passage or with the exhaust passage throughout the traverse movement of the operating piston.
10. A pressure-operated mechanism comprising an operating element, means for biasing the operating element at one side thereof, valve mechanism for controlling the building up and relief of pressure at the other side of the operating element, a valve, a pressure-responsive device connected to the valve mechanism to secure initial movement thereof to connect the pressure supply or the exhaust with the operating element, and a connection between the operating element and the valve mechanism to assure such operation of the valve mechanism that the operating element is completely traversed in either direction.
11. Pressure-operated mechanism comprising an operating element, a spring co-operating with one side of the operating element, pressure supply and exhaust connec-

tions, a valve for affording communication of either of said connections with the other side of said operated element, a pressure-responsive device for moving the valve to an initial position for supplying pressure fluid to the operating element or for exhausting fluid therefrom, and a connection between the operating element and the valve to secure such movement of the valve resulting from movement of the operating element that the valve maintains a continuance of the connection initially established by the pressure-responsive device throughout the traverse movement of the operating element.

12. The combination with a gland construction of the steam and water type for a steam turbine, of steam and water lines for the gland construction, valves in said lines, an operating element for opening and closing the valves, pressure means for one side of the operating element, valve mechanism for controlling the building up and relief of pressure at the other side of said operating element, a pressure-responsive device connected to the valve mechanism, means for developing pressure of fluid which varies as a function of the speed of the turbine and which is connected to said pressure-responsive device, and a connection between the operating element and the valve mechanism to assure maintenance of the building-up or relief of pressure at one side of said operating element throughout the traverse movement of the latter in either direction.

In testimony whereof, I have hereunto subscribed my name this 29th day of March 1923.

WARREN B. FLANDERS.
